UNITED STATES PATENT OFFICE.

RAYMOND L. MATTOCKS, OF MONTCLAIR, AND JOSEPH D. MAHER, OF NEWARK, NEW JERSEY.

DESIGN FOR A GLASS PANEL.

45,887.

Specification for Design.

Patented June 2, 1914.

Application filed April 14, 1914. Serial No. 831,838. Term of patent 7 years.

To all whom it may concern:

Be it known that we, RAYMOND L. MATTOCKS, a citizen of the United States, residing at Montclair, in the county of Essex and State of New Jersey, and JOSEPH D. MAHER, a citizen of the United States, residing at Newark, in the county of Essex and State of New Jersey, have invented a new, original, and ornamental Design for Glass Panels, of which the following is a specification, reference being had to the accompanying drawing, forming part thereof.

The figure is a plan view of a glass panel, showing our new design.

We claim:

The ornamental design for a glass panel, as shown.

RAYMOND L. MATTOCKS.
JOSEPH D. MAHER.

Witnesses:

ELSA L. BAERENRODT,
DORA WALZ.
